CLOTHES HANGER HOLDER

Neal B. Kiggens, 777 E. Barstow, Suite C 93710, and Dan H. Landon, 222 W. Shaw, Suite 103 93704, both of Fresno, Calif.

Filed Apr. 22, 1974, Ser. No. 462,866

Term of patent 14 years

Int. Cl. D6—99; XD6—04

U.S. Cl. D6—181

Fig. 1

Fig. 2

Fig. 3

FIG. 1 is a top plan view of a clothes hanger holder embodying our new invention.

FIG. 2 is a bottom plan view thereof.

FIG. 3 is a front elevation thereof.

FIG. 4 is an end elevation thereof, the opposite end being of the same ornamental appearance.

FIG. 5 is a rear elevation thereof.

We claim:

The ornamental design for a clothes hanger holder, as shown and described.
